UNITED STATES PATENT OFFICE.

CHARLES W. CROWELL, OF SALISBURY, NORTH CAROLINA.

SUPERHEATER.

Application filed August 29, 1923. Serial No. 660,009.

This invention relates to superheaters, and particularly to superheaters for internally fired steam boilers, this application being a continuation in part of my pending application Serial No. 390,270, filed June 19, 1920.

The general object of this invention is the provision in connection with a boiler shell, of a superheating section so designed that it will superheat the steam which has been generated in the boiler proper, the superheating section being so constructed as to secure economy in building, economy in pairing, and economy of fuel consumption.

A further object consists in means for regulating the temperature in the superheating section, and provide means whereby when the superheated steam is not being used the superheated steam may be caused to circulate through the cold water of the boiler barrel and thus be condensed to a state of saturated steam and returned to the superheating section, said means for causing the circulation of the superheated steam back through the condensed pipe being cut off when the superheated steam is being used.

A still further object is to provide means whereby the superheating area shall be greatly increased without decreasing the steam generating area.

Another object is to provide means controlled by the throttle valve of the superheating section whereby to cut off the passage of the products of combustion to the heating flues of the superheating section and discharge said products through the regular stack and acting automatically when the superheating section is being used to shut off passage through the regular stack and cause the discharge of products through the superheating flues, either once or a number of times, and then discharge them through a stack associated with the superheating flues.

Still another object is to provide means whereby the superheating shell and allied parts may be, as a unit, readily connected to or disconnected from the regular boiler.

A further object is to provide automatically operated means acting when the throttle valve controlling the flow of superheated steam from the superheater is opened to cause the closure of the stack which leads directly from the boiler and acting to cause the opening of said closure permitting the passage of the products of combustion directly out of said stack when the throttle

valve leading from the superheater is closed.

Other objects will appear in the course of the following description.

My invention is illustrated in the accompanying drawings, wherein:—

Figure 1 is a longitudinal sectional view through a general type of boiler showing my superheater applied thereto;

Figure 2 is a longitudinal sectional view of a modern boiler showing my superheater applied thereto;

Figure 3 is a section on the line 3—3 of Figure 1;

Figure 4 is a section on the line 4—4 of Figure 1;

Figure 5 is a fragmentary elevation of the boiler and superheater showing the damper actuating means, the cylinder 47 being partly broken away;

Figure 6 is a fragmentary enlarged section on the same plane as Figure 1 but showing the detachable connection between the boiler and the superheater;

Referring to these drawings, and particularly to Figure 1, 10 designates the fire box of an ordinary boiler having the usual rear water leg 11 and the front water leg 12 and having a manhole 13 in the boiler sheet of any usual or suitable construction. The boiler is provided with the many longitudinally extending water flues 14 connecting at their forward and rear ends with the water legs 11 and 12, a baffle wall 15 being disposed in advance of the fire box 10 so as to cause the products of combustion to pass upward from the fire box around the various flues 14 and then downward into the space 16 in advance of the baffle wall. The water leg 12 opens into a water chamber 17 which is disposed beneath the portion 16 and the baffle wall 15, the inner and outer sheets of the boiler, designated respectively 18 and 19, being connected by the usual stay bolts.

Disposed in advance of the boiler is a smoke box 20 defined by a sheet 21 and by a sheet 22 and extending through the boiler sheet 19 and opening into the smoke box is a stack 23, the lower end of which is bell-shaped, this stack being normally closed by a damper or valve 24 mounted upon a rock shaft 25 which extends transversely through the smoke box and which is operated, as will be hereafter described.

Mounted within the smoke box and in

rear of the wall or sheet 22 is a relatively thick wall 26 which for nearly its entire height is spaced from the sheet 22 but at its upper end extends over into contact with this sheet so that thereby a space 27 is provided for a purpose to be later stated.

It will be seen from Figure 6 that the sheet or wall 22 has attached to it an annular flange 28 which is riveted, or otherwise attached to the sheet 29 of the superheater section and that bolted to the margin of this angular flange 28 is a smoke ring 30 and that this in turn is riveted, bolted or otherwise attached to the end of sheet 19, this construction being such that the superheater, as will be later described, may be removed as a unit from or attached as a unit to the body of the boiler. The sheet 29 which defines or forms the exterior wall 20 of the superheater has at one end the wall 22 and inwardly of this wall 22 there is provided the flue sheet or wall 31, the space 32 between these two walls constituting a water leg, this space being connected at its upper end to the water leg 12 by means of the pipes 33 and at its lower end by means of the pipes 34. At the forward end of the superheater there is disposed a smoke box 35 which is separated from the superheater proper by means of the flue sheet 36. Flues 37 extend from the sheet 22 to the sheet 36 and open at one end into the smoke box 20 and at the other end into the smoke box 35. The superheating chamber 38 is disposed between the walls 36 and 31 and is traversed by these flue pipes 37.

In Figure 1, I have illustrated three sets of flue pipes *a*, *b* and *c*. The pipes *a* open from the smoke chamber 20 into the smoke chamber 35, as do the pipes *c*, which act as return pipes. These pipes *c* are disposed so as to open into the heating chamber 27. The pipes *b* extend from the heating chamber 27 and open into a chamber 39, from which extends a stack 40 and a forced draft nozzle 41 opens into the chamber 39 in axial alignment with the stack 40, this forced draft nozzle being connected to a source of exhaust steam in the usual manner.

Connecting the fire box with the smoke box 20 are a series of flues 42 and the products of combustion passing over the baffle wall 15 discharge through these flues into the smoke box 20. In advance of these flues 42 and extending downward to the smoke box is a baffle 43 which causes the products of combustion issuing from the flues 42 to be forced downward against the lower portion of the wall 26 and then to rise upward over the face of this wall and toward the stack 23. If the damper 24 is closed, these products of combustion will pass through the flue pipes of the series *a* and pass into the smoke box 35, then pass downward and back through the series of flues *c* into the

chamber 27 and pass upward and through the series of flues *b* into the chamber 39 and thence out of the stack 40. If, however, the damper 24 be opened the products of combustion will pass directly up through this stack 23 by natural draft or may be assisted by the steam nozzle 44 which is connected to any suitable source of steam. It will be seen from Figure 1 that the water level *x* is at a height equal to the upper end of the water leg 32 so that this water leg 32 will be at all times filled with water.

For the purpose of operating the damper 24, I mount this damper 24 upon the shaft 25, as heretofore stated, and dispose upon the exterior of the boiler means for automatically operating this damper. To this end the shaft 25 is provided with a weighted arm 45 (see Figure 5) which normally acts to rotate the shaft in a direction to open the damper, and also attached to this shaft is the grooved sector 46, and mounted upon the exterior of the boiler is a longitudinally extending cylinder 47 having an outlet opening 48 at one end, and operating within this cylinder is the piston 49 which has the piston rod 50 operatively connected by a chain or cable 51 to the grooved sector. Thus when steam is admitted in front of the piston, the piston will be forced backward and will rotate the shaft 25 and carry the closure 24 into engagement with the stack 23. When, on the other hand, steam is allowed to exhaust from the cylinder 47, the weighted arm 45 and weight of damper 24 will act reversely to cause the opening of the closure 24 and to shift the piston reversely.

The cylinder 47 is connected by a pipe 52 to a pipe 53 which leads from a throttle valve casing 54, this throttle valve casing containing therein an ordinary throttle valve opening to the interior of the superheater. Thus when the throttle valve is opened and steam passes out from the superheater into the casing 54 and then through the pipe 53, steam will also pass along the pipe 52 and act upon the piston 49 to automatically close passage through the stack 23. When, however, the throttle valve is closed and the passage of superheated steam prevented, then the steam which is within the cylinder 47 will pass out through the pipe 52 and into the pipe 53 and so to the cylinders of the engine and out, which will permit the damper to again open under the action of the weighted arm and weight of damper 24.

While I have illustrated a particular means for automatically actuating the damper 24, I do not wish to be limited to this means, as it is obvious that many other different means might be used for this purpose and I have only illustrated a particular device in order to clearly show one manner in which the damper may be automatically operated.

Connecting the boiler shell with the superheater are one or more pipes 55 whereby saturated steam from within the upper portion of the boiler may be carried into the superheater wherein it becomes superheated and it is discharged to its point of use through the throttle 54. In order to particularly prevent any part of the superheater from becoming too hot when superheated steam is not being used or because of any accident or mishap, I provide one or more pipes 56 which lead from the top of the superheater back into the boiler shell 19 and particularly into the water space 12 between the flue sheet of fire box 10 and flue sheet 21. After this pipe has entered the water space it is coiled, convoluted or bent in any other suitable form so as to secure a relatively large amount of surface and extends downward through the water leg connecting and extending through shell 19 at a relatively low point and connects to a pipe 57 which extends downward and to the lowest point in the superheater into which it enters and discharges. Disposed in the length of pipe 56 is a valve 58, which valve has an arm operatively connected to the throttle valve arm by means of a link 59 so that both the throttle valve 54 and the valve 58 are operated in unison. When the throttle valve 54 is closed, the valve 58 is opened and vice versa, and thus when the throttle valve is closed and the valve 58 is opened, the superheated steam is permitted to pass through pipe 56 into the boiler shell 19 where it is subjected to the condensing effect of the cold water in the water leg and is returned as saturated steam to the lowest point of the superheating chamber 38, thus securing a constant circulation and condensation of the superheated steam, thus maintaining an even temperature in the superheater until superheated steam is desired again, when the throttle valve 54 is opened and the valve 58 is correspondingly closed, which stops the circulation through the condensing pipe 56.

In Figure 1, I illustrate the application of my invention to a general type of boiler, while in Figure 2 I illustrate the application of my improved superheater to a modern boiler, this boiler being of the same area as the area of the boiler in Figure 1. In this view, I illustrate the fire box 10, the water leg 11, the outer boiler sheet 19 and the inner boiler sheet 18. The fire box, however, is not as extended as it is in Figure 1 and the water leg or water space 12 is much more extended than in Figure 1, and thus the flues 42 are longer than in Figure 1. These flues open into the smoke box 20, as in Figure 1, and against the baffle wall 43. Within this smoke box is the upwardly extending stack 23 with its damper 24 mounted upon the shaft 25. The exhaust steam nozzle 44 is adapted to direct steam upward through the stack 23 to cause a forced draft. So far the only difference between the construction shown in Figure 1 and that shown in Figure 2 is that in Figure 2 a dome 60 is provided which secures additional area for the saturated steam. Forward of the stack 23 there is a flue sheet 22^a which is the same as the flue sheet 22, except that it extends up to the top of the smoke box 20, and forward of this flue sheet 22^a is the flue sheet 31^a which also extends upward to the top of the smoke box. Between these flue sheets there is a water leg 32^a but inasmuch as these flue sheets extend up to the full height of the boiler a space 61 is left between the flue sheets at their upper ends within which saturated steam accumulates in the same way that saturated steam accumulates above the water level in the boiler. These flue sheets are connected at their upper ends by means of tie bolts 62.

Passing through the flue sheets 22^a and 31^a, through the superheating chamber 38, and through the sheet or wall 36^a which forms the end of the superheating chamber are the flues 37^a. These flues are not arranged in series as illustrated in Figure 1 for the reason that in Figure 2 the products of combustion are designed to pass in one way through the flues and not to be returned. These flues open into the smoke box 35^a, which is precisely the same as the smoke box 35, except that it has therein a petticoat pipe 62 discharging upward into the stack 63, and below the petticoat pipe there is provided the exhaust steam nozzle 41^a. Connected to the nozzle is the screen 64, and also connected to the nozzle and extending downward therefrom is the draft sheet 65. Under these circumstances the products of combustion will be forced through the stack 63 by the exhaust steam from the nozzle 41^a, but there will be no return as there is in Figure 1. The two flue sheets 31^a and 36^a are stayed by upwardly and centrally extending stays 66 connected to the enclosing wall or sheet of the superheater. From the superheater extends the throttle valve casing 54 and the pipe 53. The structure shown in Figure 2 is also provided with the connecting pipes 33 and 34 and the pipe 56 leading from the superheater back into the water leg of the main boiler and the pipe 57 connecting this water leg to the lower portion of the superheater. It is to be understood, of course, that the closure 24 for the stack 23 is of the same construction and is operated in the same manner as in Figure 1 and by the same mechanism.

It will be understood that in Figure 1 the shell 29 may be made any desired size to correspond to the cylinders of any locomotive regardless of their height or the size of the shell 19 and at the same time have all

the flues in the water wall 32^a submerged. In the structure shown in Figure 1, the superheater may be made nearly as large as the boiler shell 19 or as small as desired without the use of the stays 66 such as are shown in Figure 2.

It will also be noticed that owing to the cylindrical form of the superheater shell 29 and its connections, as shown in Figure 1, 10 it enables me to extend fire tubes to the top of the sheet 36, increasing the heating area in the same size flue sheet, a difference as shown in flue sheet 36^a, Figure 2, and at 15 the same time eliminate the steam space in the upper part of water leg 32.

Attention is called to the fact that in my construction I provide a superheater with a water leg or water space disposed at its rear end and a smoke box connected to it at its 20 forward end, which superheater is a unit and removable, with its smoke box as an entirety from its connection with the forward end of the boiler or with the smoke box at the forward end of the boiler. Furthermore, 25 it is to be particularly noted that my superheater is not disposed within the boiler shell and not disposed within a smoke box but that it is connected to the end of the boiler shell by means of the connection head 28 so 30 that it may be readily removed from this position or put in engagement with an old boiler and the smoke box thereof and as far as I know, such a structure as this is entirely new with me. My superheater with its rear 35 water compartment or space is disposed between two smoke boxes, each provided with a stack and is not disposed within a smoke box having stacks at its opposite ends. For this reason the cylindrical shell 29 of the 40 superheater is not limited in area and is not limited either in diameter or in length or elevation.

The connection head 28 is of great value in my invention in that this head and the 45 parts in front of it, namely, the superheater shell and the forward smoke box, may be kept in stock to fit any size head and thus be applied to boilers now in use without using the expensive tapered construction and 50 further this construction eliminates unnecessary space and expensive staying, as shown by 66 in Figure 2. By the use of this head or ring 28 the form of superheater and smoke box illustrated in Figure 1 may be used in 55 place of that form of superheater and smoke box illustrated in Figure 2.

I claim:—

1. The combination with a steam boiler 60 and a smoke box at one end having a stack, the steam boiler being formed to provide a smoke box and a water leg, of a superheater including a superheating section disposed in advance of the smoke box, a water leg disposed between the superheating section and the smoke box, a second smoke box disposed

in advance of the superheating section and having a stack, fire tubes extending through the second named water leg and through the superheating section and connecting the smoke boxes, a discharge connection from the 70 superheating section and including a throttle valve, means for causing the passage of products of combustion through the stack of the first named smoke box when said throttle valve is closed or causing the passage of the 75 products of combustion through the fire tubes and the stack of the second named smoke box when the throttle valve is opened, circulation pipes connecting the second named water leg with the first named water 80 leg, a condensing pipe extending through the water leg of the boiler, a connection from one end of said condensing pipe to the upper portion of the superheating section and from the lower end of said condensing pipe to the 85 lower portion of the superheating section, a valve for preventing or permitting the passage of steam from the superheating section into the condensing pipe, and means causing the automatic opening of said valve when 90 the throttle valve is closed and the automatic closing of said valve when the throttle valve is opened.

2. The combination with a boiler having 95 the usual smoke box and stack at its forward end, of a superheater secured to the front end of said smoke box and comprising a cylindrical shell divided into two sections to provide a front superheating section and a rear water leg section, a smoke box to which the forward end of the superheater is connected, and fire tubes extending through both the water leg and the superheating section and communicating at their opposite ends with both smoke boxes. 100

3. As an article of manufacture a superheater adapted to be applied as a unit to boilers, comprising an outer shell divided into two sections by an intermediate wall, the front section being a superheating section 110 and the rear section being a water leg, a smoke box engaged with the forward end of said superheating section, and fire tubes extending longitudinally through said water leg and the superheating section and opening 115 at one end into said smoke box and at the other end opening through the rear wall of the water leg.

4. A superheater structure adapted to be applied as a unit to the smoke box of a 120 boiler, comprising an outer shell having three tube sheets spaced apart and secured therein and dividing the interior of the shell into two sections, the forward section being a superheating section and the rear section 125 constituting a water leg, a smoke box secured to the forward end of the shell and having a stack, and fire tubes extending longitudinally through the water leg and through the superheater section and opening 130

at their forward ends into the forward smoke box and at the rear ends opening through the rearmost tube sheet.

5. The combination with a boiler having the usual smoke box at its forward end, the smoke box having a stack, of a superheater structure comprising a cylindrical shell, three tube sheets spaced apart therein to thereby form a rear water leg and a forward superheating section, a forward smoke box engaged with the forward end of said shell, the rear wall of the smoke box being formed by the forward tube sheet, and the forward smoke box having a stack, fire tubes 10 extending longitudinally through the superheater and water leg, opening at their forward ends through the forward tube sheet into said forward smoke box, and at their rear ends opening through the rear tube 15 sheet and into the smoke box at the forward end of the boiler, and an annular connection head connecting the rear end of said shell with the forward end of the boiler smoke box.

25 6. The combination with a boiler having a fire box, a smoke box and a stack leading therefrom, fire tubes communicating with said fire box and smoke box and a smoke box ring secured in the front end of the 30 smoke box, the boiler terminating at said smoke box, of a superheater structure disposed in advance of the smoke box and including an exterior shell and an annular connection head secured to the shell and to said smoke box ring whereby the superheater may be applied to or removed from the smoke box of the boiler as an entirety.

35 7. The combination with a boiler having a fire box, of front and rear smoke boxes each having a discharge stack, fire tubes 40 extending between and communicating at their ends with said rear smoke box and fire box, of a superheater secured between said front and rear smoke boxes and comprising a cylindrical shell divided into two sections, the front section being a superheating section and the rear a water leg section, fire 45 tubes extending through both the water leg and superheating sections and communicating with said front and rear smoke boxes, an automatically operated damper in the rear smoke box for directing and discharging the products of combustion received from said fire box through said fire tubes 50 into the rear smoke box and out of the stack thereof when superheated steam is not being used or discharging said products through the fire tubes in the water leg and superheating sections into said front smoke 55 box and through the stack thereof when superheated steam is being used, a saturated steam conveying pipe, water conveying pipes, and a superheated steam condensing

60 pipe, said superheater section connecting with said saturated steam pipe and the superheated steam condensing pipe and the water leg communicating with said water pipes.

65 8. The combination with a boiler having a fire box, a smoke box in advance thereof having a discharge stack therein, and fire tubes extending between and communicating at their ends with said fire box and smoke box, of a superheater detachably secured to the front end of said smoke box 70 and consisting of a cylindrical shell having three tube sheets spaced apart and secured therein and dividing the interior of the shell into two sections, the forward section constituting a superheating section and the rear section 75 constituting a water leg between the superheating section and said smoke box, another smoke box having a discharge stack therein secured to the forward end of said cylindrical shell, and fire tubes extending 80 longitudinally through said water leg and superheating sections and secured in said tube sheets and communicating with said smoke boxes.

85 9. The combination with a boiler having a fire box, a smoke box in advance thereof and having a discharge stack therein, fire tubes extending between and communicating at their ends with said fire box and smoke box, of a superheater detachably secured to the front end of said smoke box consisting of a cylindrical shell having three tube sheets spaced apart and secured therein dividing the interior of the shell into two sections, the forward section being a superheating section and the rear section constituting a water leg between the superheating section and said smoke box, another smoke 90 box having a discharge stack therein and secured to the forward end of said superheating section, fire tubes extending longitudinally through said water leg and superheating sections, the fire tubes being secured in said tube sheets and communicating with said smoke boxes, a damper operating in conjunction with said smoke box and the stack of the boiler and allowing the products of combustion received from the fire box to 95 pass out through said stack when superheated steam is not being used but closing the path of travel through said stack when superheated steam is being used and simultaneously directing the flow of the products of combustion from said smoke box through 100 said water leg and superheating sections and said forward smoke box and stack to the discharge.

105 In testimony whereof I hereunto affix my signature.

CHARLES W. CROWELL.
